CLAIM

The ornamental design for a microcircuit for smart card, as shown and described.

DESCRIPTION

1. Microcircuit for smart card

2. Microcircuit for smart card

1.1 : Front

1.2 : Back

1.3 : Right

1.4 : Left

1.5 : Top

1.6 : Bottom

1.7 : Perspective

1.8 : Perspective

2.1 : Front

2.2 : Back

2.3 : Right

2.4 : Left

2.5 : Top

2.6 : Bottom

2.7 : Perspective

2.8 : Perspective
